UNITED STATES PATENT OFFICE.

PETER THEODOR TKATZSCHENKO, OF BROOKLYN, NEW YORK.

ATTACHMENT FOR WATER-CLOSETS.

No. 867,170.

Specification of Letters Patent.

Patented Sept. 24, 1907.

Application filed October 7, 1905. Serial No. 281,821.

To all whom it may concern:

Be it known that I, PETER THEODOR TKATZSCHENKO, a subject of the Emperor of Russia, and residing at Brooklyn, in the county of Kings and State of New

5 York, have invented certain new and useful Improvements in Attachments for Water-Closets, of which the following is a specification.

My invention relates to water closet attachment and more particularly to the addition of sanitary 10 means to the seat of the closet and the convenient attachment of toilet paper thereto. These and other details and objects of my invention are more fully described in the following specification and set forth in the appended claims.

15 In the drawings accompanying this specification and forming a part thereof like reference characters are used to designate the same parts in the various figures and:

Figure 1 is a plan view of a water closet seat illustrating my invention. Fig. 2 is a longitudinal vertical 20 sectional view of the same on the line $x-x$. Fig. 3 is an enlarged sectional detail of one side of the seat through the line $y-y$.

To the ordinary hinged wooden seat 5 of a water- 25 closet is hinged at 6, a thin metal ring or frame 7 conforming with the shape of wooden seat but slightly larger to overlap same as shown. The ring is dished, or convex on the upper side so that it is adapted to make contact with the seat only at their respective 30 edges and between the two parts, at the joint of the greatest distance of separation, are disposed coiled springs 8 for the purpose of affording a yielding effect to the ring. The ring is also provided with lateral ears 9, perforated to receive an adjusting screw 10 of a 35 clamp 11, while two of these clamps are here shown, one on each side of the seat, more may be adopted if found desirable.

Upon the upper face of the ring 7 and held in place by the clamps 11 is a pad or series of sheets of toilet or 40 other paper 12, cut to the size and shape of the ring and having at its rear side, or any other suitable point,

a lip or flap 13 which may be found useful in separating and removing the sheets as needed for consumption, or to provide a clean and new sheet for the upper face of the pad.

45

It is obvious that I do not limit myself to the use of toilet paper alone in the application of a paper cushion to a water closet seat but may utilize paper of any quality and so treated with the proper chemicals as to form an anti-septic or thoroughly sanitary seat for a 50 water closet.

Various shapes of paper or means of securing same to the seat may suggest themselves in the practical use of this improved attachment without departing from the essential features of the invention as claimed.

55

The pad of paper and the springs afford a softer or cushioning effect for the user of the seat and the temperature and texture of the paper will add greatly to the comfort of the seat in cold weather.

What I claim as new and desire to secure by Letters 60 Patent is:—

1. In an attachment for water closets the combination with a seat having an opening, of a hinged frame or ring convex in cross-section, springs between the seat and the frame, a pad of paper having detaching means for each 65 sheet and conforming in size and shape with the ring, and adjustable clamps to secure the pad to the ring.

2. In an attachment for water closets the combination with a seat having an opening, of a thin metal ring or frame slightly overlapping the seat and dished out from 70 below and convex on the upper side whereby contact with the seat is made on the edges only, and coiled springs between the seat and the frame to make said frame yielding.

3. In an attachment for water closets the combination of a thin metal ring or frame convex in cross section and having lateral ears with an opening in each, a pad of paper having detaching means for each sheet conforming in size and shape with the ring, and adjustable clamps passing each through the opening in each ear of the ring and securing the pad to same.

In testimony whereof, I have signed my name to this specification in the presence of two subscribing witnesses, this fifth day of October 1905.

PETER THEODOR TKATZSCHENKO.
